UNITED STATES PATENT OFFICE.

WILLIAM H. LUM, OF NEW YORK, N. Y.

DESIGN FOR A CASTER-BOTTLE.

SPECIFICATION forming part of Design No. 15,619, dated December 16, 1884.

Application filed October 6, 1884. Term of patent 7 years.

To all whom it may concern:

Be it known that I, WILLIAM H. LUM, of New York, in the county of New York and State of New York, have invented certain new and useful Improvements in Designs for Bottles; and I do hereby declare the following to be a full, clear, and exact description of the invention, such as will enable others skilled in the art to which it pertains to make and use it, reference being had to the accompanying drawing, which forms part of this specification.

My design relates to caster-bottles; and it consists in the ornamental shape, which will be more fully described hereinafter, whereby the appearance of the bottle is improved and made more attractive.

The accompanying drawing represents a bottle embodying my design.

20 A represents the bottle, which has its lower portion of any suitable form as far as the

shoulder B. From the shoulder B the surface D is conical, the sides being inclined inward toward their tops, so as to contract the size of the bottle at this point. From the line F the 25 surface or part G is of a globular form, as shown, as far as the ring or enlargement H. This enlargement H forms a shoulder or projection which extends out over the top of the upper part of the globular portion. The neck 30 I of the bottle has a suitable lip, J.

Having thus described my invention, I claim—

A design for a caster-bottle, as shown and described.

35 In testimony whereof I affix my signature in presence of two witnesses.

WILLIAM H. LUM.
